(57) **CLAIM**

The ornamental design for an electronic book, as shown and described.

DESCRIPTION

FIG. 1 is a perspective view of a first embodiment of an electronic book of the present design; FIG. 2 is a front view of the electronic book of FIG. 1; FIG. 3 is a right side view of the electronic book of FIG. 1; FIG. 4 is a back view of the electronic book of FIG. 1; FIG. 5 is a left side view of the electronic book of FIG. 1; FIG. 6 is a top view of the electronic book of FIG. 1; FIG. 7 is a bottom view of the electronic book of FIG. 1; FIG. 8 is a perspective view of a second embodiment of the electronic book of the present design.

FIG. 9 is a front view of the electronic book of FIG. 8; FIG. 10 is a right side view of the electronic book of FIG. 8;

FIG. 11 is a back view of the electronic book of FIG. 8; FIG. 12 is a left side view of the electronic book of FIG. 8; FIG. 13 is a top view of the electronic book of FIG. 8; and, FIG. 14 is a bottom view of the electronic book of FIG. 8. The broken lines shown in the drawings depict portions of the electronic book that form no part of the claimed design.

1 Claim, 8 Drawing Sheets
